[57] CLAIM

The ornamental design for a cart, as shown and described.

DESCRIPTION

FIG. 1 is a front perspective view of a cart showing my new design, the broken lines representing a medical laser apparatus and associated trays positioned on the cart and shown for illustrative purposes only;

FIG. 2 is a side elevation view of the cart of FIG. 1, the laterally opposite side being a mirror image thereof;

FIG. 3 is a top plan view thereof;

FIG. 4 is a front elevation view thereof; and

FIG. 5 is a rear elevation view thereof.

FIG. 2

FIG. 1

FIG. 3

FIG. 4

FIG. 5
